FIG. 4

Inventor
Charles H. Cornwell
by *Johnston & Nichols*
Attn:

UNITED STATES PATENT OFFICE.

CHARLES HORACE COWNELL, OF HAMILTON, ONTARIO, CANADA, ASSIGNOR TO THE BURNALL CORPORATION OF CANADA, OF HAMILTON, ONTARIO, CANADA.

FUEL ECONOMIZER.

Application filed June 6, 1923. Serial No. 643,789.

To all whom it may concern:

Be it known that I, CHARLES HORACE COWNELL, a subject of the King of Great Britain, and a resident of the city of Hamilton, county of Wentworth, Province of Ontario, Dominion of Canada, have invented certain new and useful Improvements in Fuel Economizers, of which the following is the specification.

10 My invention relates to improvements in fuel economizers and more particularly to the application of such devices to fire-tube boilers, and the object of the invention is primarily to improve the efficiency of these 15 boilers by accomplishing a more complete combustion of the fuel than has hitherto been the case, thus reducing the loss due to unburnt fuel passing up the stack; a further object is to complete the combustion in 20 such part of the boiler as will enable the heat generated to be effectively absorbed by the heating surface of the boiler, a further object is to enable these results to be obtained by the fitting of a simple and inexpensive device which may be conveniently 25 and quickly attached to any boiler; and a still further object is smoke elimination.

My invention consists essentially of a 30 novel form of device mounted within and at the rear of the combustion chamber of a fire-tube boiler whereby heated oxygen is admitted in the form of a finely directed spray or as a number of very fine jets, into the rear of the combustion chamber adjacent to the mouth of the fire-tubes, all as 35 hereinafter more particularly described and illustrated in the accompanying drawings in which;—

Fig. 1 is a side elevation, partly in section, of a standard form of return tubular boiler showing my invention applied thereto.

Fig. 2 is a central vertical section of an air chamber used in my invention taken on 45 the line 2, 2 of Fig. 3.

Fig. 3 is a section on the line 3, 3 of Fig. 2 a portion of the outer inclined wall being broken away.

Fig. 4 is a top plan view of the device. 50 In the drawings like characters of refer-

ence indicate corresponding parts in the different views.

1 indicates the boiler shell of a standard return tubular boiler, 2 being the brick setting and 3 the smoke box.

4 are grate bars, 5 the ash pit, 6 the firing door, 7 the ash door and 8 the bridge.

The combustion chamber of the boiler may be divided for reference purposes into the fire box proper 9 and the rear portion located at the back of the boiler shell and adjacent to the mouths of the fire-tubes will be designated as 10.

11 is an air distributing device which comprises an enclosed hollow cast metal chamber of flat rectangular shape having its side and bottom walls inclined.

12 is an inlet pipe communicating with an inlet port 29 located centrally within the back wall of the member 11 adjacent to the upper end thereof.

The lower end of the chamber is formed with the double spaced walls 13 and 14, which walls are sloping and parallel with each other (see Fig. 2).

Each of these walls is provided with a plurality of small orifices or perforations, the orifices in the inner wall being designated by the numeral 15 and those in the outer wall by the numeral 16.

The orifices 15 and 16 are arranged in staggered relation so that the orifices in the walls 13 and 14 are not in alignment. The purpose of this will appear hereinafter.

The interior of the chamber 11 is divided into a number of communicating sections by a series of diaphragms or baffles 17, 18 and 19, the arrangement of which is shown in Fig. 3.

The baffle 17 is of arc shape and extends transversely across the device near the upper end thereof. The baffles 18 extend transversely inwardly from the two sides so that a central opening 20 is formed between the inner ends of these baffles. The baffle 19 is located centrally of the device and is in the form of an equilateral triangle with its apex directed upwardly.

This baffle 19 forms an orifice 21 extending through the device.

These baffles divide the device substantially into four chambers 22, 23, 24 and 25.

26 is a pipe leading upwardly from the inlet pipe 12 and 27 is a perforated rosette carried by the upper end of the pipe 26.

28 is the rear wall of the brick set of the boiler.

The construction and operation of my invention is as follows.

10 The device 11 is mounted upon the rear wall 28 of the boiler setting being located centrally with respect to the boiler and is so positioned that the sloping end 14 is directed downwardly and is substantially level 15 with the bottom of the boiler shell.

The operation of my device is based upon the principle of the diffusion of gases.

When the boiler is in operation air is drawn into the device through the pipe 12, 20 passes downwardly through the device and is discharged in the form of a finely divided spray or a series of fine jets through the perforations in the bottom of the device.

25 In order that the device may operate efficiently as will hereinafter be explained, it is essential that the air discharged from the device shall be highly heated and therefore it is desirable that its passage through the 30 device be rendered as slow as possible so that there will be sufficient time for the air to become heated by contact with the hot walls thereof.

For this purpose the baffles 17, 18 and 19 35 are provided and from an examination of Fig. 3 it will be noted that the air in passing through the device is deflected by these baffles and follows substantially the devious course indicated by the arrows.

40 By the provision of the orifice 21 in the device the heating surface is further increased.

The path of the gases passing from the fire box 9 is indicated by the arrows "A" in Fig. 45 1 and the air being discharged from the device 11 is indicated by the arrows "B".

The fact is fully recognized by engineers that above the fuel bed in the fire box the gases contain a high percentage of combustible matter in the form of volatile hydro-carbon and suspended free carbon but that there is not sufficient oxygen present for the combustion of this matter.

The air supply in sufficient quantities for 55 the combustion of this matter cannot be obtained by increasing the rate of air supply through the fuel bed and therefore a very large percentage of this combustible matter, which forms a considerable portion of the 60 fuel, must pass up the stack in the unburnt condition.

This results not only in considerable fuel loss and in lowered efficiency of the boiler but the suspended free carbon passes off as 65 smoke and deposits soot in the flues.

From the above it will be apparent that if this fuel is to be burnt some means of admitting sufficient oxygen for its combustion above the fuel bed must be provided.

It is with this object in view that I have 70 devised my invention.

The operation will be clearly understood from an examination of Fig. 1. The air being discharged at "B" through the device 11 supplies the necessary amount of free oxygen 75 for the combustion of the unburnt fuel above referred to.

This oxygen enters the combustion chamber in a highly heated state and by diffusion intermingles and becomes intimately mixed 80 with the hot gases rising from the fuel bed and its temperature being sufficiently high it has no cooling action on the gases.

By my invention I so arrange the device 11 with respect to the boiler shell that the 85 oxygen is supplied at the point where it will mix most effectively with the gases as they rise from the under side of the boiler shell to pass through the tubes of the boiler.

In this way sufficient oxygen is supplied 90 so that the gases may be completely burnt before they pass out of the flues and rise into the smoke box 3.

It is very desirable as has been above 95 stated that the air pass quietly out of the device 11 and with a view of obtaining a 100 quieter discharge I provide the double spaced walls 14 and 15, each of said walls being perforated but the perforations being out of alignment.

In this way the air passing through the 105 perforations 15 in the inner wall will impinge against the outer wall 14 and thus any velocity which the air might have retained in its passage through the device 11 is entirely destroyed and the air passes quietly out through the perforations 16 in the outer wall 14.

From the foregoing it will be apparent 110 that I have devised improvements in fuel economizers which will greatly improve the efficiency of boilers and such like.

Many modifications may be made in my 115 invention without departing from the spirit of the invention or the scope of the claims and therefore the exact form shown is to be taken as illustrative only and not in a limiting sense.

What I claim as my invention is:

A fuel economizer of the class described 120 comprising a flat, substantially rectangular, enclosed chamber provided with an inlet port centrally in the back wall adjacent to one end of the chamber, the opposite end wall provided with perforations, the chamber sub-divided into a plurality of communicating sections by transversely disposed baffles, said baffles consisting of an upper arc shaped baffle situated immediately before 125 the inlet port and extending into proximity 130

of the sides of the chamber, two laterally opposed baffles situated below the aforesaid arc-shaped baffle and extending inwardly from the sides of the chamber into proximity to the centre, and a lowermost baffle of triangular shape situated centrally of the chamber, the portion of the front and back walls of the chamber enclosed within the triangular baffle being removed so that a triangular opening is formed through the 10 chamber.
